UNITED STATES PATENT OFFICE

2,174,482

METHOD OF OPERATING A COMPRESSION
REFRIGERATION SYSTEM

Peter Schlumbohm, New York, N. Y.

Original application November 19, 1932, Serial No. 643,344. Divided and this application February 23, 1938, Serial No. 192,167. In Germany November 25, 1931

2 Claims. (Cl. 62—170)

The invention relates to a method of operating a compression refrigerating system. In such systems the vapor of the refrigerant is compressed by a compressor and condensed in heat exchange with a cooling medium. The cooling medium may be air, water or brine. Ice has also been suggested as a cooling medium, to cool the condenser from the outside with the ice.

Following my invention, frozen cooling medium is applied within the condenser, so that the vapor of the compressed refrigerant may contact directly the surface of the frozen cooling medium. The great advantage of this step will be evident from the following calculation: If the frozen cooling medium would be applied from the outside of the condenser wall, some five to ten centigrades would be lost for the heat transfer through the condenser wall. If water is the refrigerant and water ice is the cooling medium, this means that in the case of my method the true vapor pressure of water ice, 4.5 mm. Hg., would represent the condenser pressure, whereas as in the other case the condenser pressure might easily rise to pressures like 9 mm. Hg.

Assuming that the water-refrigerant is evaporating in the evaporator at a pressure of 2.25 mm. Hg., the ratio of compression would have to be 1:4 if the known art was applied and could be reduced to 1:2 if my new method is used.

Lowering the ratio of compression is of special importance if the compressors, which are required to compress the refrigerant, are of the type of the centrifugal compressor or of the type of the jet compressor, and just these types are applied with preference for handling the large volume of refrigerant vapors as to be handled per B. t. u. in the case of such refrigerants like water.

The invention is illustrated diagrammatically, partly in section and partly in view, in the accompanying drawing. The compressors shown are of the type of the jet compressor. They could be replaced by centrifugal compressors or any other suitable type of compressor without changing the principle of the invention to be illustrated.

A compressor 1 is pumping the vapor of the refrigerant 15 from an evaporator 2 into a condenser 3. The suction tube of the compressor

is designated 5 and the pressure tube (exhaust) is designated 4. The condenser 3 is filled with the frozen cooling medium 8, which practically will be in most cases frozen water. The frozen cooling medium is e. g. placed on a grill 6 to allow the melted cooling medium and the condensed refrigerant to drip off and to be withdrawn from the bottom of the condenser by means of a tube 7. Following my invention it is important to withdraw these liquids quickly and constantly from the condenser before they would be warmed up by the condenser walls and cause higher pressures in the condenser than the pressure of the frozen cooling medium, which in the case of water ice is 4.5 mm. Hg. Following my invention this low pressure of 4.5 mm. Hg. is further protected against the higher pressure of the jet of a water jet pump 19 by providing a liquid column S in the syphon trap 20. This arrangement makes it possible to withdraw liquids from the 4.5 mm. Hg. pressure domain of the condenser into the about 12 mm. Hg. pressure domain of the water jet pump's suction chamber.

Following my invention, the low pressure in the condenser 3 is furthermore maintained by providing an air pump 21 to withdraw non-condensable gas like air through tube 9 from the condenser. The exhaust tube 10 of the air pump may be connected to the suction chamber of the water jet pump 19, as illustrated, the latter one working as pre-vacuum pump for the pump 21.

Having now described the nature of my new method and having given an example of the manner in which it may be performed, what I claim is:

1. The method of operating a compression refrigeration system in which refrigerant vapor is compressed and condensed in a condenser in heat exchange with a cooling medium, comprising the step of condensing the compressed refrigerant vapor in direct contact with frozen cooling medium and absorbing the condensation heat of the refrigerant by the melting of the cooling medium.

2. The method as claimed in claim 1, comprising the additional step of constantly withdrawing from the condenser liquid refrigerant and liquid cooling medium.

PETER SCHLUMBOHM.
